UNITED STATES PATENT OFFICE.

JAMES TIBURCE FELIX CONTI, OF PARIS, FRANCE.

FLUID-PRESSURE REGULATOR.

SPECIFICATION forming part of Letters Patent No. 556,402, dated March 17, 1896.

Application filed September 9, 1895. Serial No. 561,910. (No model.)

To all whom it may concern:

Be it known that I, JAMES TIBURCE FELIX CONTI, of the city of Paris, France, have invented Improvements in Fluid-Pressure Regulators, of which the following is a full, clear, and exact description.

Pressure-regulators as heretofore used for enabling a gas compressed at a certain pressure to be utilized at another pressure, either fixed or variable, automatically cut off the communication between the motor and reservoir when the pressure on the motor attains the degree desired, the communication being re-established at each expenditure of the pressure, thus effecting the distribution of the gas at a pressure which may be constant or be varied by hand. The apparatus forming the subject of the present application for Letters Patent has for its object, on the contrary, to enable the pressure in the interior of a completely-closed chamber to be varied at will without any expenditure of gas. Thus, for example, the apparatus when applied to compressed-air brakes permits of varying by hand the pressure of the air acting on the brake-pistons to any desired extent.

Reference is to be had to the accompanying drawings, forming part of this specification, in which—

Figure 1 represents a cross-section on line 12, and Fig. 2 an axial section of the regulator.

The same letters denote like parts in both figures.

The apparatus comprises two valves a' a^2 upon the same spindle b and serving to control communication with the chambers c and d respectively. e is a piston, upon which bears a spring f , which abuts at its other end against a screw-gland g abutting against a cross-head h through the nut i and lock-nut j , whereby the initial tension of the spring is regulated. The cross-head h is connected by rods k to the cylinder l , in which fits as a piston the body portion m , the cylinder l having a ring n , whereby tractive force may be applied to cross-head h by any suitable means. The chamber c communicates by a pipe connected to o with a high-pressure reservoir, and chamber d communicates by passage p with the receiver in which the pressure is to be regulated, which, in the present example, would be the brake-cylinders.

The action of the apparatus is as follows: Supposing a certain tractive force to be applied to ring n and transmitted to cross-head h , the movement of the latter through a given distance will produce the following effects: The spring f will first move down the piston e and cause the closure of valve a^2 on its seat and cut off the communication of chamber d with the external air. The continued motion of the piston e , which then carries with it both valves a' a^2 , causes valve a' to open communication between chambers c and d , whereby the reservoir of fluid under pressure is put in communication with the receiver in which it is desired to modify the pressure. Immediately the fluid which has passed through the valve a' into chamber d exerts pressure upon piston e superior to that of spring f the piston e rises, valve a' is closed by a spring q , and the receiver, the brake-cylinder in the present case, being no longer in communication with the reservoir of compressed air, the pressure in the brake-cylinder will remain constant and equal to that on the side of the piston e next the chamber d , which is balanced by that of the spring f . If now the cross-head h is retained in a fixed position, the pressure in the brake-cylinder will remain constant independently of the tightness of the joints, for should a leakage occur in the brake-cylinder the pressure in chamber d will fall, the equilibrium will be disturbed, and piston e under the action of spring f will again open valve a' and admit the fluid under pressure from chamber c until equilibrium is restored.

It will thus be seen that for each position of cross-head h there is a corresponding and different pressure equal to the stress of the spring f on the piston e at that position.

If it be desired to diminish the pressure within the receiver (the pressure within the brake-cylinders in the example under consideration) it is only necessary to allow the cross-head h to rise to a suitable extent, whereupon the equilibrium on piston e being disturbed by the pressure within d exceeding that exerted by the spring f the piston e will rise and cause valve a^2 to open and allow the escape of air from d , and consequently from the receiver, until the pressure therein again becomes equal to that of the spring f . Thus by means of the apparatus a given pressure

may be maintained in a closed receiver and may be varied at will by pulling on the ring *n*.

The cylinder *l*, in which the body portion works as a piston, constitutes a safety appliance when the regulator is applied to air-pressure brakes. If the connections with *n*, through which the operation of the brake mechanism is controlled, were to fail, the engine-driver could nevertheless control the brakes by turning on a cock, admitting compressed air through *r* to the cylinder *l*, which is thereby moved downward and with it the cross-head *h*, with the result above described.

The nuts *i,j* enable the tension of the spring to be regulated to correspond to the minimum pressure first required, whereby with the same apparatus and the same spring different variations of pressure may be obtained for the same motion of the cross-head *h*, whatever may be the pressure of the reservoir. Thus, for example, the pressure may be varied as well from nothing to six kilos as from fifteen to twenty-five kilos by merely regulating the initial tension of the spring.

It is to be understood that this regulator may be applied to all the purposes for which regulators now in use are employed.

I claim—

1. The herein - described double - acting pressure-regulator, consisting in the combination of the two chambers *c,d*, the one in communication with the fluid under pressure and the other with the receiver in which the pressure is to be regulated, the chamber *d* being closed by a piston *e* which balances the regulated pressure, a spring bearing upon said piston to move the same, a movable support for said spring, valves *a',a²* connected together and respectively controlling the com-

munication between the chambers *c,d* and 40 between chamber *d* and the open air, the opening and closing of said valves being determined by the piston *e*, substantially as specified.

2. In the herein-described fluid-pressure 45 regulator, the safety appliance consisting in the combination, with the regulator proper comprising the chambers *c,d*, valves *a',a²*, spring-pressed piston *e*, cross-head *h*, of the cylinder *l* coupled thereto and in which the 50 body portion works as a piston under the pressure of fluid admitted to said cylinder for controlling the regulator in case of use, substantially as specified.

3. The herein - described double - acting 55 pressure-regulator, consisting in the combination of two chambers *c,d*, the one in communication with the fluid under pressure and the other with a receiver in which the pressure is to be regulated, the chamber *d* being 60 closed by a piston which balances the regulated pressure, a spring bearing upon said piston to move the same, means for adjusting the tension on said spring and a movable support therefor, valves *a',a²*, connected together 65 and respectively controlling the communication between the chambers *c,d*, and between chamber *d* and the open air, the opening and closing of said valves being determined by the piston *e*, substantially as specified. 70

The foregoing specification of my improvements in fluid-pressure regulators signed by me this 24th day of August, 1895.

JAMES TIBURCE FELIX CONTI.
